UNITED STATES PATENT OFFICE.

CONRAD DIEHL, OF ST. LOUIS, MISSOURI.

IMPROVEMENT IN PERSPECTIVE-DRAWING APPARATUS.

Specification forming part of Letters Patent No. **156,209**, dated October 27, 1874; application filed March 25, 1874.

To all whom it may concern:

Be it known that I, CONRAD DIEHL, of the city and county of St. Louis and State of Missouri, have invented an Apparatus embodying the principles of Object-Drawing, of which the following is a specification:

It is the object of my apparatus to illustrate the task of reproducing the impression which the eye receives of real objects upon a plane.

A in the annexed drawing represents a horizontal plane, tablet, or other support, upon which the object to be drawn is placed. On the edge of this table is vertically erected the frame C C, to which a net, of equal squares, B, is fastened, representing the picture-surface. This net of lines may be constructed of cords or wires, or may be engraved upon a glass plate, which is slid into the frame. A number of squares, equal to those through which the object is seen from a fixed point of view, being traced on the drawing-paper, the student is enabled to inscribe the bounding-

lines and details of an object into the squares on the paper as they appear inscribed in the squares of the apparatus. A set-screw, D, working against a cleat, E, or some other suitable contrivance, is attached to the support A for the purpose of fastening the same to a desk or drawing-table.

The principal advantage of my invention consists in its application for use in schools, as it exercises the eye of the pupil and impresses upon his mind the first idea of graphical reproduction with the greatest facility.

What I claim as my invention, and desire to secure by Letters Patent, is—

The drawing apparatus herein described, consisting of the upright frame C, cross-wires, cords, or lines B, support or tablet A, cleat E, and set-screw D, all substantially as specified.

CONRAD DIEHL.
